UNITED STATES PATENT OFFICE

ETTORE VIVIANI, OF MILAN, ITALY

APPARATUS FOR DRY-SPINNING ARTIFICIAL TEXTILE FIBERS WITH RECOVERY OF THE VOLATILE SOLVENTS

Application filed September 19, 1928, Serial No. 306,940, and in Italy April 7, 1928.

In operating the so-called dry-spinning process (particularly when acetylcellulose and nitrocellulose solutions are employed) the recovery of the volatile solvents passing off in the form of vapor has hitherto been effected in a great variety of ways. All these ways, however, were characterized in that the air (or other gas) laden with the vapors of the solvent and removed from the spinning cell, was wholly or partially freed from said vapors. The removal of the solvent-laden air was effected by means of pumps or fans, and in all cases the gaseous mixture, consisting of air and solvent vapors, was withdrawn from the spinning cell, so that the gaseous mixture in the interior of the cell was in a continuous state of flow.

This circumstance indirectly entailed the necessity for cooling the whole of the gaseous mixture led out of the cell, and for reheating it after the recovery of the solvent.

In other words, it was always necessary in practice to heat and cool large volumes of air or gas, whereas all that should really be needed is to introduce and remove the amount of heat required for the vaporization and condensation, respectively, of the solvent.

The object of the present invention is to obviate the aforesaid drawbacks, or at least 30 to restrict the cooling and subsequent heating of the gaseous mixture present in the cell to a small quantity thereof. The invention, which enables the spinning to be conducted in closed cells, renders it unnecessary to remove and cool the gaseous mixture which fills the spinning cell, by providing a limited surface which is cooled to an adequate degree, in the spinning cell itself. This temperature should be so calculated that it does not exceed 35 the temperature of the spinning cell (measured in the immediate vicinity of the filament) and is, in any event, below the boiling point of the solvent or solvents.

If the vapor tension of the solvent in the 45 spinning cell exceeds the value corresponding to the temperature of the coolest spot within the cell, then condensation will take place there. Consequently, in the cell forming the subsequent of the present invention, the gaseous and liquid phases of the solvent or solv-

ents are always present, in addition to the spinning solution issuing from the nozzle.

The solvent or solvents present in the liquid state are alone continuously withdrawn, a circumstance which constitutes one of the 55 important characteristics of the present invention.

Moreover, this arrangement also enables the vapor concentration of the volatile solvent in the spinning cell to be regulated at will, 60 by adjusting the temperature of the cooling surface.

Embodiments of the invention are illustrated diagrammatically in the accompanying drawing in which:

Fig. 1 is a diagrammatic vertical section through a spinning cell;

Fig. 2 is a similar view of a modification; and

Fig. 3 is a similar view of another modification.

According to Fig. 1 the jacket space B enables the spinning cell A to be warmed by means of hot air, hot water or steam. Inside the cell are disposed one or more tubes C 75 through which cold water or brine is circulated for cooling purposes.

As already mentioned, the vapor tension of the solvent vapors formed during the spinning process tends to attain the value corresponding to the temperature of the cooling device. The cooling water or brine enters the tube C at C' and issues therefrom at E. F is the spinning nozzle, and H the winding bobbin. If now the spinning cell be heated 80 in such a manner that rapid and complete vaporization of the solvent contained in the spinning solution issuing from the spinning nozzle takes place, continuous condensation of the solvent will occur on the cooling surface, since the vapor tension cannot exceed a certain value. The condensate can be readily removed by way of the funnel D and collected.

The apparatus may, of course, vary in design. Thus, in Fig. 2 the cooler consists of a plain tube C through which water or brine is circulating. In this case the condensed solvents collect in the lowermost part of the spinning cell, and are drawn off through the 100

siphon S. The spinning cell is heated by means of a heating jacket B having inlet and outlet connections T^1 T ; but the heating may also be effected in any other way, such as by heating coils, electrical resistance and so forth, without departing from the scope of the invention.

Fig. 3 represents still another embodiment. Here the cooler is confined to the lowermost part of the cell. The upper part is heated by the liquid circulating in the heating jacket B, which it enters at T^1 and leaves at T . The lower part is cooled by the cooling jacket B¹ through which water or brine at a suitable temperature is circulated. This latter arrangement insures a quiescent filament during the spinning process, since the gentle currents resulting from the sinking of the vapors from the hot to the cold zone of the cell facilitate the spinning process itself.

By means of the apparatus herein described, 90-95% of the solvent contained in the spinning solution can always be recovered and, under favorable conditions, still higher values are obtained. The amount of solvent retained in the wound filament is small, and, if proper temperatures be maintained, does not exceed 5% of the weight of the fiber.

The solvents recovered in this manner are in a high state of purity, and can be used again without intermediate distillation.

Obviously, the invention is not restricted to the embodiments specified, and it will be readily understood that variations may be made without departing from the scope of the invention as defined by the appended claims.

I claim:

1. In the apparatus for dry spinning artificial textile fibers with recovery of the solvent contained in the spinning solution, the combination of a spinning cell provided with a spinning nozzle, means for effecting vaporization and condensation of the solvent within the cell while in direct open communication with the body of the vapors therein, and means for collecting the condensate.

2. In apparatus for dry-spinning artificial textile fibers with recovery of the solvent contained in the spinning solution, the combination of a spinning cell provided with a spinning nozzle, means for effecting vaporization and condensation of the solvent so that the cell contains solvent in the gaseous and liquid condition in addition to the spinning solution issuing from the nozzle, and means for withdrawing only the solvent present in liquid form from the cell whereby the vapor tension of the solvent vapors is maintained at constant value during the spinning process.

3. In apparatus for dry-spinning artificial textile fibers with recovery of the solvent contained in the spinning solution, the combi-

nation of a spinning cell and means in the cell for condensing the solvent vapors and recovering the solvent.

4. In apparatus for dry-spinning artificial textile fibers with recovery of the solvent contained in the spinning solution, the combination of a spinning cell, means for cooling to the condensation point solvent vapors located within the cell, and means for collecting the condensate. 70

5. In apparatus for dry-spinning artificial textile fibers with recovery of the solvent contained in the spinning solution, the combination of a spinning cell, means for condensing the solvent vapors inside the cell without changing the average temperature of the gaseous media filling the cell, and means for collecting the condensate. 80

6. In apparatus for dry-spinning artificial textile fibers with recovery of the solvent contained in the spinning solution, the combination of a spinning cell, means for condensing the solvent vapors inside the cell without changing the average temperature of the gaseous media filling the cell, and means for withdrawing the condensed solvent from the cell. 90

7. A spinning cell for use in dry-spinning artificial textile fibers with recovery of the solvent contained in the spinning solution having, in combination, means for heating the cell, and means in the cell for condensing solvent vapors. 95

8. A spinning cell for use in dry-spinning artificial textile fibers with recovery of the solvent contained in the spinning solution having, in combination, means for heating the cell, means for the circulation of cooling fluid to effect condensation within the cell of the solvent vapors, and means for collecting the condensate. 100

9. A spinning cell for use in dry-spinning artificial textile fibers with recovery of the solvent contained in the spinning solution having, in combination, means for heating the upper portion of the cell, means for cooling the lower portion of the cell to the temperature of condensation of the solvent vapors within the cell, and means for collecting the condensate. 110

10. A spinning cell for use in dry-spinning artificial textile fibers with recovery of the solvent contained in the spinning solution having, in combination, a jacket for the circulation of a heating medium surrounding the cell, cooling means for condensing solvent vapors within the cell, and means for collecting the condensate. 120

11. A spinning cell for use in dry-spinning artificial textile fibers with recovery of the solvent contained in the spinning solution having, in combination, means for heating the upper portion of the cell, means for cooling the lower portion of the cell to the temperature of condensation of the solvent 125

120

vapors within the cell, and means including a siphon for collecting and withdrawing the condensate from the cell.

12. A spinning cell for use in dry spinning

5 artificial textile fibers with recovery of the solvent contained in the spinning solution, means for condensing within the cell vapors of said solvent, and means for collecting the condensate.

10 13. A closed spinning cell for use in dry spinning artificial textile fibers with recovery of the solvent contained in the spinning solution, means for condensing within the

cell vapors of said solvent, and a siphon for 15 removing the condensate from the cell.

14. In a process of dry-spinning artificial silk by extrusion of a spinning solution into a cell containing heated gas in which the solvent evaporates, the step which comprises 20 condensation within the cell of the solvent vapor.

15. A process of dry spinning artificial silk including continuous extrusion of a spinning solution into a cell, continuously passing 25 over the filament thus formed a heated gas in which the solvent evaporates, and continuously condensing within the cell the solvent from said gas.

16. A process as set forth in claim 15 in 30 which the heated gas passes through the upper portion of the cell and is condensed in the lower portion of the cell.
